His Attorney

UNITED STATES PATENT OFFICE.

ROBERT M. GILSON, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

Application filed July 17, 1926. Serial No. 123,066.

My invention relates to railway signaling, and particularly to signaling of the type wherein the supply of current to a track circuit is periodically interrupted for the purpose of controlling traffic governing mechanism, such, for example, as mechanism carried by a railway train.

One feature of my invention is the provision, in a system of the type mentioned, of means for controlling a signaling device by the current in such a track circuit in such manner that the device will not be affected by the periodic interruptions of the supply of current to the track rails.

I will describe two forms of apparatus embodying my invention, and will then point out the novel features thereof in claims.

In the accompanying drawing, Fig. 1 is a diagrammatic view showing one form of apparatus embodying my invention. Fig. 2 is a diagrammatic view showing a modification of the apparatus shown in Fig. 1 and also embodying my invention.

Similar reference characters refer to similar parts in each of the views.

Referring first to Fig. 1, the reference characters 1 and 1^a designate the track rails of a railway track along which traffic normally moves in the direction indicated by the arrow. These rails are divided by insulated joints 2 to form a track section A—B, and this track section is provided with a track circuit comprising a source of current located at the exit end of the section and a track relay D connected across the rails at the entrance end of the section. As here shown, the source of track circuit current is a transformer T, the secondary 3 of which is connected across the rails of section A—B through an impedance 5, and the primary 4 of which is supplied with alternating current from the secondary 6 of a line transformer U^B. The primary 7 of transformer U^B is constantly supplied with alternating current from a suitable source, not shown in the drawing, and the same thing is true of the primary 7 of line transformer U^A, herein-after referred to.

The section A—B is provided with coding means C for periodically interrupting the supply of current from the transformer U^B to the transformer T. As here shown, this coding means comprises a relay having a back contact 8 interposed between the transformer

U^B and the transformer T. Relay C is provided with a circuit which passes from the secondary 6 of the transformer U^A, through back contact 9 of track relay D, winding of relay C, and back contact 17 of relay C to secondary 6 of transformer U^A. It will be seen, therefore, that when track relay D is de-energized, that is, when section A—B is occupied by a train, relay C will be intermittently energized, and so will periodically interrupt the supply of current to the track rails from transformer U^B. The coding relay C will usually be controlled in part by traffic conditions in advance of section A—B, but this control forms no part of my present invention. Furthermore, back contact 9 of track relay D may be omitted from the circuit for relay C, so that the coding relay C will operate continuously.

The reference character E designates a relay which is supplied with energy from the track rails of section A—B. As here shown, the primary 14 of a transformer G is connected across the rails, and the secondary 15 of this transformer is connected with the relay E through the medium of the rectifier F comprising four asymmetric units 10, 11, 12 and 13. These units are connected in such manner as to constitute a full-wave rectifier, whereby uni-directional current is supplied to the relay E each time that alternating current is applied to the track circuit, that is, each time that back contact 8 of coding relay C is closed. It will be observed that the asymmetric units 11 and 10 constitute a shunt path for relay E, which path offers a low resistance to current induced therein by the decay of flux in the relay core when the relay becomes de-energized, and it will also be observed that the asymmetric units 13 and 12 constitute a similar shunt path. It follows that during each interruption of track circuit current these shunt paths retard the decay of flux in the relay core and so retard the opening of the relay armature. This retardation is sufficient to prevent the relay armature from opening during the periodic interruptions of track circuit current while the coding relay C is in operation.

When a train enters section A—B, it de-energizes the track relay D and so sets the coding relay C into operation. When the train reaches a point close to the transformer G, it reduces the current supplied to

relay E to such a value that this relay opens, and the relay thereafter remains open until the train leaves section A—B. Track relay D then becomes energized, so that the operation of the coding relay C stops, whereupon alternating current is continuously supplied to the track rails of section A—B and relay E again becomes energized.

Relay E may be utilized to control any desirable signaling means, such, for example, as a highway crossing signal S, located adjacent point B. This signal S is controlled by a back contact 16 of relay E, through a circuit which is obvious from the drawing, and so it follows that the signal S will be set into operation when a train approaches transformer G and will cease operation after the train passes point B.

With the apparatus shown in Fig. 1, I have found that as a train approaches the transformer G, the voltage applied to relay E is gradually reduced until a value may be reached at which the relay does not receive enough energy to remain closed during the interruptions of the track circuit current, with the result that for a short distance of train movement the relay E may intermittently close and open its contact 16. To avoid this possible intermittent operation of relay E, the relay may be supplied with energy in the manner illustrated in Fig. 2. Referring to this view, the asymmetric units 11 and 12 are interposed between transformer G and the winding of relay E in the same manner as in Fig. 1, but the connections between transformer G and relay E which include the other two asymmetric units 10 and 13 also include front contacts 18 and 19, respectively, of the relay E. It follows that when the relay E is energized, full wave uni-directional current is supplied to the winding of this relay, whereas when the relay is de-energized, one half of each wave is supplied to the winding through asymmetric units 11 and 12, but the other half of each wave is prevented from flowing in the winding of the relay. With the structure shown in Fig. 2, when a train approaches transformer G, it will reach a point at which relay E will open during an interruption of the track circuit current, and thereafter the relay will receive only one half of each alternating current wave. Since the voltage required to pick up the relay E on one-half of an alternating current wave is about four times the voltage required to pick it up when supplied with full wave uni-directional current, it will be clear that once the relay is opened in response to a train approaching transformer G, it will not close again until the train has passed point B and normal voltage is again applied to the transformer G. Full wave uni-directional current will then again be applied to relay E, so that this relay will

remain energized until another train approaches transformer G.

One feature of my invention is that it is unnecessary to make the relay E slow-releasing in character, and another feature is that it is unnecessary to interpose a second relay between relay E and the track rails.

Although I have herein shown and described only two forms of apparatus embodying my invention, it is understood that various changes and modifications may be made therein within the scope of the appended claims without departing from the spirit and scope of my invention.

Having thus described my invention what I claim is:

1. In combination, a section of railway track provided with a source of current, coding means for periodically interrupting the supply of current from said source to the rails of said section, a relay receiving energy from said rails, rectifying means interposed between said rails and said relay and constituting a shunt path around the relay which prevents the relay from releasing its armature during the interruptions of current while said coding means is in operation, and signaling means controlled by said relay.

2. In combination, a section of railway track provided with a source of alternating current, coding means for periodically interrupting the supply of current from said source to the rails of the section, a relay, rectifying means interposed between the track rails and said relay for supplying the relay with uni-directional current from the track rails while alternating current is being supplied to the rails through said coding means, said rectifying means constituting a shunt around the relay to prevent the relay from releasing its armature during the interruptions of current by said coding means, and signaling means controlled by said relay.

3. In combination, a section of railway track provided with a source of alternating current, coding means for periodically interrupting the supply of current from said source to the rails of the section, a relay, rectifying means interposed between the track rails and said relay for supplying the relay with uni-directional current while alternating current is being supplied to the rails through said coding means, said rectifying means constituting a shunt around the relay to prevent the relay from releasing its armature during the interruptions of current by said coding means, means controlled by the armature of said relay for removing a portion of said rectifying means from the circuit for the relay when the relay armature is open, and signaling means controlled by said relay.

4. In combination, a section of railway

- track provided with a source of alternating current, coding means for periodically interrupting the supply of current from said source to the rails of the section, a relay, two asymmetric units interposed between the track rails and the two terminals respectively of the winding of said relay for permitting one half of each alternating current wave but not the other half to flow through said winding, two other asymmetric units interposed between the track rails and the two terminals respectively of said winding for the second half of each wave but not the first to flow through said winding, and signaling means controlled by said relay.
5. In combination, a section of railway track provided with a source of alternating current, coding means for periodically interrupting the supply of current from said source to the rails of the section, a relay, two asymmetric units interposed between the track rails and the two terminals respectively of the winding of said relay for permitting one half of each alternating current wave but not the other half to flow through said winding, two other asymmetric units interposed between the track rails and the two terminals respectively of said winding for permitting the second half of each wave 25 but not the first half to flow through said
- winding, the connections between the relay winding and the track rails through the second pair of asymmetric units including front contacts of said relay whereby the supply of the second half of each wave to 35 the relay winding is discontinued when the relay armature is open, and signaling means controlled by said relay.
6. In combination, a section of railway track provided with a source of alternating current, coding means for periodically interrupting the supply of current from said source to the rails of the section, a transformer the primary of which is connected with the rails of said section, a relay receiving energy from the secondary of said transformer, and rectifying means interposed between the secondary of said transformer and said relay for supplying the relay with unidirectional current while alternating current 40 is being supplied to the rails through said coding means, said rectifying means constituting a shunt around the relay to prevent the relay from releasing its armature during the interruptions of track circuit current by 45 said coding means, and signaling means controlled by said relay.
